SAFETY ATTACHMENT FOR CAR-COUPLER
LOCKSSylvester L. Joiner, Sweetwater, Tex., assignor of
three-fourths to Robert E. Graves, Brownwood,
Tex.

Application August 25, 1941, Serial No. 408,268

1 Claim. (Cl. 213—146)

This invention relates to a safety attachment for a car coupler lock lifter; and it is primarily an object of the invention to provide an attachment of this kind to be rested on the coupler head of the lift pin for the lock disposed therethrough, said attachment being so formed and constructed to provide means to prevent the lift pin from binding and also to substantially eliminate the liability of the lock being accidentally released as the result of undue vibration of the train while in motion.

When the train is traveling along a rough trackway, or the car wheels are flat, or there is a slack in the train, and more particularly in connection with a freight train, there is a tendency of the train to slack between cars with a resultant liability of the lock for the knuckle to shake loose and the train break. It is a further object of the invention to provide an attachment for coaction with the lock pin to prevent such accidental release of the lock.

The invention consists in the details of construction and in the combination and arrangement of the several parts of my safety attachment for car coupler locks whereby certain important advantages are attained, as will be hereinafter more fully set forth.

In order that my invention may be better understood, I will now proceed to describe the same with reference to the accompanying drawings, wherein:

Figure 1 is a view partly in elevation and partly in section illustrating an attachment constructed in accordance with an embodiment of my invention in applied position.

Figure 2 is a fragmentary detail sectional view taken substantially on the line 2—2 of Figure 1 with parts in elevation.

Figure 3 is a view in perspective of the attachment unapplied.

Figure 4 is a view in top plan constructed in accordance with another embodiment of my invention.

Figure 5 is a sectional view taken substantially on the line 5—5 of Figure 4.

Figure 6 is a view in top plan of a still further embodiment of my attachment.

Figure 7 is a sectional view taken on the line 7—7 of Figure 6.

Figure 8 is a view in top plan of an attachment constructed in accordance with a still further embodiment of the invention.

Figure 9 is a sectional view taken substantially on the line 9—9 of Figure 8.

Figure 10 is a view in top plan of an attachment constructed in accordance with an additional embodiment of the invention, and

Figure 11 is a sectional view taken substantially on the line 11—11 of Figure 10.

As particularly illustrated in Figures 1 to 3 of

the drawings, H denotes a coupler head comprised in a well known type of coupler as for example the American Railroad Association D coupler. Associated with the head H in the usual manner is a knuckle 1 held in closed position by a lock 2. The top wall 4 of the head H is provided with the usual opening 5 through which is directed the lock pin 6. The upper portion of the pin 6 is operatively engaged with a lift lever L. The foregoing features form no part of my invention but are already known and in use. When the parts of the coupler head H are set, the pin 6 slides downwardly and rearwardly for coaction with the anti-creeping lip 3, as is well known in connection with the standard D coupler of the top operated form, as illustrated in the accompanying drawings.

It often occurs that the shocks and jars to which the rolling stock of a train, and more particularly a freight train, are subjected results in such undue vibration of the lock 2 to free the same from its lip 3 so that the knuckle 1 is allowed to swing open with a resultant breaking of the train. This disadvantage often occurs as the result of the car of a train having flat wheels and also upon slackening of the train and which slackening has a tendency to occur when the train is traveling over a light roadway. This disadvantage may be overcome by retarding any accidental vibration of the lock by restricting the tendency of the lock pin 6 to move upwardly under adverse conditions. My improved attachment A is for this purpose.

As herein embodied, my attachment A comprises a substantially rectangular rigid collar 7 which is placed directly upon the top wall 4 of the head H and through which the pin 6 is freely disposed. The central opening or slot 8 of this collar 7 is sufficient to allow for the free raising and lowering of the pin 6 when desired to adjust the pin 6 into lock set or knuckle throw position. As particularly illustrated in Figure 2 of the drawings, the cross sectional configuration of the pin 6 and the form of the opening or slot 8 is such as to render the collar 7 non-rotatable around the pin 6, thus assuring the maintenance of the inclined edges a in desired position.

The collar 7 is of metal, preferably cast, although I do not wish to be understood as limiting myself in this respect. The side marginal portions of the collar 7 are defined by the upstanding flanges 9 with the inner end portions of these flanges 9 connected by an upstanding intermediate web 10 herein disclosed as integral with the rear portion of the collar 7 and with the adjacent end portions of the flanges 9. The upper edges a of these flanges 9 are inclined from their rear ends to their forward ends on a suitable angle and preferably at about 45° although, of course, this angle of inclination may be varied,

as the requirements of practice may deem necessary. As particularly illustrated in Figures 1 and 2, the flanges 9 extend beyond the forward end of the opening 8 of the collar 7 and have their forward ends or low points merged with the collar 7 at the forward edge thereof.

When the lock 2 is set, the lift lever L will contact the inclined edges a of the flanges 9 with the result that the pin 6 will have a tendency under its own weight to move downwardly or inwardly of the coupler head under sufficient stress to hold the lock 2 set against release as a result of the shocks and jars incident to train travel as, for example, flat wheels, train slack, rough track, and the like. It may be stated that the pin 6 is of sufficient weight to cause the lever L with which it is engaged to have a constant tendency to ride downwardly of the inclined edges a. It is also to be particularly pointed out that by having the lever L ride on the edges a of the flanges 9, the lock pin 6 is substantially suspended from the lever L and maintained against binding against the forward edge wall of the opening 3.

As is clearly illustrated in Figure 1 of the drawings, the lip 3 serves as a fulcrum for the lower end of the pin 6 so that said pin readily swings or rocks lengthwise of the opening 2 and which opening is of a length materially in excess of the width or corresponding dimension of the pin 6. This movement of the pin 6 assures the maximum efficiency of the attachment A. It will be noted that the central opening or slot 8 of this attachment A is also of a length materially in excess of the width or corresponding dimension of the pin 6.

In the embodiment of the invention as illustrated in Figures 4 and 5, the attachment B is placed on the top wall of the head of the coupler with the lock pin disposed therethrough as hereinbefore set forth with respect to the first embodiment of the invention. This attachment B comprises a substantially U-shaped member with its side arms 11 rearwardly disposed and the upper faces b of the arms 11 are inclined downwardly and forwardly, such inclination being extended over the forward and intermediate portion 12 of the attachment B. The open space at the rear of the attachment B is closed by a removable member 14 insertible through the free end portions of the side arms 11 and bridging the space therebetween. In either applying or removing the attachment B, the member 14 is, of course, removed. After application the member 14 is applied, thus insuring the attachment B being maintained in working position with respect to the lift pin and the top of the coupler head.

As illustrated in Figures 4 and 5, the member 14 comprises a cotter pin and freely mounted on this member or pin 14 between the free end portions of the arms 11 is a roller 15. This roller 15 facilitates the desired raising or lowering of the lock pin to adjust the lock into set or knuckle free position.

The attachment C as illustrated in Figures 6 and 7 comprises a substantially rectangular link, the bars of which are formed of relatively heavy material and with the side bars 16 thereof substantially parallel. One of the end or cross bars 17 is split, as at 19, to provide means whereby, upon spreading of said split bar 17, the attachment may be applied to or removed out of working position without releasing the lock pin from the lift lever. The opposite or unbroken cross end bar 19 has welded or otherwise rigidly se-

cured to its under surface a depending flange 20 which has direct contact with the top wall of the coupler head with the result that the attachment C is disposed on a forward or downward incline on a desired angle.

In Figures 8 and 9, the attachment D is also in the form of a rectangular link having its side bars 21 substantially parallel and with one of its cross end members 22 split, as at 23. The side bars 21 of the attachment D adjacent to an end of the attachment are upwardly buckled, as at 24, whereby the forward portions c of the side bars 21 are disposed on a downward and forward incline.

In the form of the invention as illustrated in Figures 10 and 11, the attachment E comprises a plate member 25 having a relatively large central opening 26 through which the lift pin is adapted to be freely disposed. Rigidly secured by welding or otherwise, as may be preferred, to the rear portion of the plate 25 and for a major distance therealong is an upwardly inclined and substantially U-shaped member 27. The side arms 28 of this member 27 have their inner edges formed to substantially conform to the adjacent edge portions of the openings 26. This plate 26 is extended downwardly and forwardly on a required incline and interposed between the rear portion of the member 27 and the plate 25 is a filler bar 29 rigidly secured by welding or the like to both the member 27 and the plate 25. This applied bar 29 assures the maintenance of the member 27 with respect to the plate 25. The rear portion of the edge of the plate 25 defining the opening 26 and the rear edge portion of the member 27 immediately thereabove are provided with the notches or recesses 30 to facilitate the desired movement of the lock pin through the attachment.

From the foregoing description it is thought to be obvious that a safety attachment for car coupler locks constructed in accordance with my invention is particularly well adapted for use by reason of the convenience and facility with which it may be assembled and operated.

I claim:

In combination with the coupler head and lift pin of a standard D top operated car coupler and a lifting means for the pin, the opening in the top wall of the coupler being of a length materially in excess of the width or corresponding dimension of the pin, the coupler having an internal part providing a coupling for the inserted end of the pin to allow the pin to have swinging movement along the slot, a member positioned upon the top of the coupler head and having an opening through which the lift pin freely passes, said opening being also of a length materially in excess of the width or corresponding dimension of the lift pin to permit swinging movement of the pin, said member at opposite sides of the opening therethrough being provided with upstanding flanges, the upper edges of the flanges being inclined downwardly and forwardly, a part of the lifting means for the pin being adapted to ride on the inclined edges when the coupler lock is in operative position, said part of the lifting means sliding downwardly on said edges inwardly of the coupler head under sufficient stress to hold the lock of the coupler against release as a result of shocks and jars.

SYLVESTER L. JOINER.
